UNITED STATES PATENT OFFICE.

JOHN WILLIAM PIERCY AND JAMES RAYMOND HOWARD, OF SCUNTHORPE, ENGLAND.

PACKER FOR BLOOMS AND THE LIKE.

1,359,195.

Specification of Letters Patent. Patented Nov. 16, 1920.

Application filed March 7, 1918. Serial No. 221,017.

To all whom it may concern:

Be it known that we, JOHN WILLIAM PIERCY, subject of the King of Great Britain and Ireland, residing at 3 Diana street, Crosby, Scunthorpe, in the county of Lincolnshire, England, and JAMES RAYMOND HOWARD, subject of the King of Great Britain and Ireland, residing at Tawstock, Cole street, Scunthorpe, in the county of Lincolnshire, England, have invented a certain new and useful Improved Packer for Blooms and the like, of which the following is a specification.

This invention relates to improved means for packing or loading together a number of blooms, billets, bars and other similar objects so that such bundle of objects can be more easily handled, the object of the present invention being the provision of means whereby a number of separate articles can be automatically fed to the apparatus and be so placed in position relatively to each other that the whole bundle of articles can be readily handled and the combination with such means of provision for enabling a chain, sling or the like to be placed under the bundle of articles.

In the accompanying drawings:—

Figure 1 is a side elevation of the improved packing apparatus provided with feeding rollers.

Fig. 2 is a longitudinal sectional elevation of the same.

Fig. 3 is a plan of the same.

Fig. 4 is a transverse section on the line A, B, Fig. 2, showing also a lifting chain or sling, and

Fig. 5 is a section, to an enlarged scale, of part of the machine bed plate.

The drawing illustrates the improved packing apparatus as arranged for the packing of blooms or billets in connection with rolling mills, and fitted with feeding rollers.

The bed plate 1 may be of any desired length and width and its upper surface is provided with a number of transverse grooves 2 from the bottom of which the lower face of the groove slopes upwardly in a forward direction toward the top 3 of the next groove. The section of the bed is thus approximately ratchet or saw toothed as shown in Fig. 5, but the shape of the grooves and of the inclines may be varied provided there are no edges or projection which would prevent the forward move-

ment of an article slipping in a forward direction upon such bed and so that there is a clear passage through the groove when the top opening thereto is closed by articles 60 upon the bed. At the sides of the bed there are a number of uprights 4 which are sufficiently strong to withstand the strain thrown upon them and are so arranged that the spaces 5 between the uprights correspond with the entrances to the grooves 2 in the bed plate and the uprights are preferably so placed or shaped that their vertical edges offer no obstruction to the forward movement of the articles. The upper 70 end of each upright, is, or may be, provided with a groove 6 or its equivalent for receiving and positioning a plate 7 which forms an end or abutment to the length of bed in use, and the lower end of the plate 75 7 may be held in a similar manner. The position of the plate 7 is changed in accordance with the length of the articles to be packed.

The blooms or billets, in the arrangement 80 shown are delivered to the improved apparatus by positively driven rollers 8 which are constructed, arranged, and driven according to any usual method. The surface speed of these rollers and their height above 85 the bed plate are so designed and arranged that the billets 9, Fig. 1, delivered by the end roller fall into approximately the position shown in Fig. 2, with the center of the billets approximately over the entrance 90 to one of the grooves 2 on the bed plate 1 and at the end of the roller frame 10 there is an end plate 11 by which the packed billets are held clear of the end roller when being secured.

The teeth on the upper surface of the bed plate may be integral with such plate or they may be attached thereto and in the latter case are readily replaceable if broken or worn, also the articles to be packed may 100 be delivered by a traveling band, an inclined chute or other equivalent means instead of the feeding rollers.

By means of the apparatus herein described the billets are automatically packed 105 or loaded upon the bed plate 1 and when a sufficient number have been so packed or loaded a chain, sling, or the like 12, Fig. 4, is passed through the groove 2 under such bundle and the bundle is removed by a crane 110 or like means. The chain or sling may however be placed in the groove before the load-

ing or packing is commenced and for longer articles two or more chains or slings may be used to each bundle.

What we claim as our invention and desire to obtain by Letters Patent is:—

1. In an apparatus for the packing of blooms or billets, the combination of a bed plate, a feeding device at one end of said bed plate, transverse grooves in such bed plate, the sides of the grooves remote from the feeding device being inclined upwardly from their bases in a direction away from the feeding device, upright bars at both sides of the bed plate and an end plate for limiting the length of the bed in use substantially as herein set forth.
- 10
- 15

2. In an apparatus for the packing of blooms or billets, the combination of a feeding device, a bed plate, transverse grooves in the face of said bed plate, said grooves being of ratchet formation lying in a direction away from the feeding device, upright bars at both sides of the bed plate and an adjustable end plate supported by said upright bars and engaging at its lower extremity in any of the grooves.

JOHN WILLIAM PIERCY.
JAMES RAYMOND HOWARD.
